CLAIM

The ornamental design for a filter housing for use in a microbial water sampler, as shown and described.

DESCRIPTION

FIG. 1 is a front perspective view of a filter housing for use in a microbial water sampler showing my new design; FIG. 2 is a front view thereof; FIG. 3 is a top plan view thereof; FIG. 4 is a right side view thereof; FIG. 5 is a left side view thereof; FIG. 6 is a bottom view thereof; and, FIG. 7 is a cross sectional view thereof at line 7-7 of FIG. 3.

The broken lines are for the purpose of showing environmental structure only and form no part of the claimed design.
